(57) **ABSTRACT**

A crash attenuator for decelerating an impacting vehicle includes a first end that can be releasably secured to a vehicle, and a second end that is longitudinally spaced from the first end. The second end includes an impact member that is movable in the longitudinal direction from a pre-impact position to an impact position. At least a pair of spaced deformable attenuator members extend in a longitudinal direction and have a proximal end and a distal end. The proximal ends are staggered downstream from the impact member in the pre-impact position. At least a portion of the deformable attenuator members are bent in a non-outboard direction as the impact member is moved from the pre-impact position to the impact position.

CRASH ATTENUATOR

Matter enclosed in heavy brackets [ ] appears in the original patent but forms no part of this reissue specification; matter printed in italics indicates the additions made by reissue; a claim printed with strikethrough indicates that the claim was canceled, disclaimed, or held invalid by a prior post-patent action or proceeding.

This application is a continuation of U.S. application Ser. No. 12/349,056, filed Jan. 6, 2009, now U.S. Pat. No. 8,074,761 which claims the benefit of U.S. Provisional Application No. 61/019,488, filed Jan. 7, 2008, the entire disclosures of which are hereby incorporated herein by reference.

BACKGROUND

The present invention generally relates to a crash attenuator capable of attenuating energy during a crash, and in particular, a crash attenuator coupled to a vehicle such as a truck.

Crash cushions, for example truck mounted attenuators (TMAs), are commonly used to protect utility vehicles and workers engaged in roadside construction or maintenance, as well as the occupants of cars traveling on the roadways, in the event of a collision. TMAs are designed to safely stop an errant vehicle from an otherwise dangerous and potentially fatal collision with the rear end of an unprotected utility vehicle. Typically, TMAs are secured to the rear of the utility vehicle and cantilevered away from the vehicle in a rearward direction. In other embodiments, TMAs are configured as towable trailers.

One criteria for measuring the effectiveness of a TMA is through the crash test specification outlined in the National Cooperative Highway Research Report 350 "Recommended Procedures of the Safety Performance Evaluation of Highway Features," or NCHRP 350. Under the tests in this specification, an occupant of both light and heavy vehicles must experience less than a 12 m/s change in velocity (ΔV) upon contacting the vehicle interior and less than a 20 g deceleration after contact.

Unlike ground mounted crash cushions, TMAs cannot rely on tracks, cables, or rails to help stabilize energy absorbing materials acting in compression. In the event the energy absorbing material should become unstable, the TMA's ability to effectively absorb energy could be compromised. Many prior art systems have employed large bearing areas or collapsible frame linkages to prevent buckling of the energy absorbing materials as they are compressed during vehicle impact. However, collapsible frame linkages and the like can be complicated and expensive to manufacture.

Furthermore, many existing TMAs create sharp metal debris, as a result of the energy absorption process, that pose serious safety hazards to roadway workers in the vicinity of the TMA, as well as the driver and passengers of the impacting vehicle. Thus, a need presently exists for a crash attenuator that meets the NCHRP 350 standards, is relatively inexpensive to manufacture, and prevents debris from producing a hazard to roadway workers in the vicinity of the TMA, or to the driver and passengers of the impacting vehicle.

BRIEF SUMMARY

In one aspect, a crash attenuator includes a first end adapted to be releasably secured to a vehicle, and a second

2

end that is longitudinally spaced from the first end. The second end includes an impact member that is moveable in the longitudinal direction from a pre-impact position to an impact position. The crash attenuator also includes at least a pair of laterally spaced deformable attenuator members extending in a longitudinal direction that, in one embodiment, have a circular cross section. When a vehicle impacts the crash attenuator, at least a portion of the deformable attenuator members are bent in a non-outboard direction as the impact member is moved from the pre-impact position to the impact position.

In another aspect, a crash attenuator includes a first end adapted to be releasably secured to a vehicle, and a second end that is longitudinally spaced from the first end. The second end includes an impact member that is moveable in the longitudinal direction from a pre-impact position to an impact position. The crash attenuator also includes at least one pair of spaced apart deformable attenuator members. The deformable attenuator members have a proximal end and a distal end. The proximal ends are positioned downstream from the impact member in a longitudinally staggered relationship when the impact member is in the pre-impact position. When the impact member moves from the pre-impact position to the impact position, at least a portion of the deformable attenuator members are bent in a non-outboard direction.

In yet another aspect, a crash attenuator includes a first end and a second end that is longitudinally spaced from the first end. An impact member is movably located at the second end. The crash attenuator also includes an energy absorbing member disposed between the first and second ends. The energy absorbing member is configured to absorb energy when the impact member is moved from a pre-impact position to an impact position. The impact member includes an impact surface having a substantially central portion lying substantially in a laterally extending vertical plane, and opposite side portions that extend laterally outward and longitudinally toward the first end from the central portion, such that each of the side portions is non-parallel to the vertical plane.

In one embodiment, a crash attenuator includes a first end and a second end that is longitudinally spaced from the first end. An impact member is movably located at the second end. The crash attenuator also includes an energy absorbing member disposed between the first and second ends. The energy absorbing member is configured to absorb energy when the impact member is moved from a pre-impact position to an impact position. At least a pair of deforming members is coupled to each of the opposite sides of the impact member. Each pair of deforming members includes an inboard deforming member positioned adjacent to an inboard side of the deformable attenuator member, and an outboard deforming member positioned adjacent to an outboard side of the deformable attenuator member. The outboard deforming member is positioned longitudinally downstream from the inboard deforming member.

A method of decelerating a vehicle with a crash attenuator includes providing a crash attenuator that includes a first end that is adapted to be releasably secured to a vehicle, and a second end that is longitudinally spaced from the first end and includes an impact member, at least a pair of laterally spaced deformable attenuator members extending in a longitudinal direction, a deforming member that is disposed around and engaged with a portion of at least one of the deformable attenuator members, and a deflecting member disposed at the first end; impacting the impact member with a vehicle; deforming the deformable attenuator members

with the deforming member downstream of the impact member; and forcing the deformed attenuator members against the deflecting member, and thereby bending the deformable attenuator members in a non-outboard direction.

In another aspect, a method of decelerating a vehicle with a crash attenuator includes providing a crash attenuator including an impact member, at least a pair of laterally spaced deformable attenuator members having a circular cross section and extending in a longitudinal direction, a deflecting member, and a suspension member that is fixedly coupled to the impact member such that it is movable with the impact member; spacing the deformable attenuator members away from the deflecting member, such that when a vehicle impacts the impacting member, the first [end does] ends of the deformable attenuator members do not immediately engage the deflecting member; impacting the impact member with a vehicle; and bending the deformable attenuator members when the impact member moves from a pre-impact position to an impact position.

In another aspect, a crash attenuator includes a first end that is secured to a vehicle and a second end that includes an impact member and is longitudinally spaced from the first end. The crash attenuator also includes a suspension member that is fixedly coupled to the impact member and moveable therewith, and an attenuator member disposed between the first and second ends. When the impact member moves from a pre-impact position to an impact position, the attenuator member is configured to deform and thereby absorb energy.

The crash attenuator provides significant advantages over other crash attenuators. For example and without limitation, the deformable attenuator members provide the energy dissipation while also serving as the framework for the attenuator, thereby reducing the cost and complexity of the system. In addition, the deformable members are deformed, for example by shaping and/or bending, and are not severed or ruptured into various pieces. As such, the system remains intact and does not produce loose road debris.

In one embodiment, the deformable members are deformed in a non-outboard direction, such that they do not provide a snagging or spearing component. In one embodiment, the staggered configuration of the deformable members provides a more even ride-down distribution. In addition, the shape and configuration of the impact surface and member helps to ensure that the central portion thereof is the first and primary area to engage an impacting vehicle, thereby reducing an eccentric loading of the laterally spaced deformable members.

The foregoing paragraphs have been provided by way of general introduction, and are not intended to limit the scope of the following claims. The presently preferred embodiments, together with further advantages, will be best understood by reference to the following detailed description taken in conjunction with the accompanying drawings.

BRIEF DESCRIPTION OF THE DRAWINGS

FIG. 1 is a perspective view of a first embodiment of a crash attenuator.

FIG. 2 is a close-up perspective view of an impact end of the attenuator shown in FIG. 1.

FIG. 3A is a partially exploded perspective view of an impact member shown as viewed from the hitch end of the attenuator shown in FIG. 1.

FIG. 3B is a partially exploded perspective view of the impact member shown in FIG. 3A, as viewed from the impact end of the attenuator shown in FIG. 1.

FIG. 4 is a partially exploded perspective view of the hitch end of the attenuator shown in FIG. 1.

FIG. 5A is a perspective view of a downstream deforming structure as shown in FIG. 1.

FIG. 5B is a front view of a portion of the downstream deforming assembly shown in FIG. 5A.

FIG. 5C is a side view of a deforming member shown in FIG. 5B.

FIG. 5D is an alternative embodiment of the deforming member shown in FIG. 5C.

FIG. 6 is a close-up perspective view of the suspension assembly shown in FIG. 1.

FIG. 7 is a perspective view of the attenuator shown in FIG. 1 before impact with a vehicle.

FIG. 8A is a top view of an alternative embodiment of a deflector member.

FIG. 8B is a close-up perspective view of the alternative embodiment of the deflector member shown in FIG. 8A.

FIG. 9A is a top view of a second alternative embodiment of a deflector member before impact.

FIG. 9B is a top view of the second alternative embodiment of the deflector member shown in FIG. 9A after impact.

FIG. 9C is a partial perspective view of the second alternative embodiment of the deflector member shown in FIG. [9B] 9A before impact.

FIG. 10A is a perspective view of an alternative embodiment of a crash attenuator.

FIG. 10B is a partial top view of the alternative embodiment of the crash attenuator shown in FIG. [9A] 10A with portions of the frame assembly removed to reveal the deflecting members.

FIG. 11 is a top view of a fixed crash attenuator.

DETAILED DESCRIPTION OF THE DRAWINGS AND THE PRESENTLY PREFERRED EMBODIMENTS

The term "longitudinal" refers to the lengthwise direction 1 between an impact end 120 and an attachment end 180 of a crash attenuator 100, and is aligned with and defines an axial impact direction generally parallel to the arrow 2 indicating the direction of traffic flow in FIGS. 1, 2, 7, 10A, 10B and 11. The term "front," "forward," "forwardly," and variations thereof refer to the position or orientation relative to the attachment end 180, which connects the crash attenuator 100 to a maintenance vehicle 3 or the like, while the term "rear," "rearward," "rearwardly," and variations thereof

refer to the position or orientation relative to the impact end 120 of the crash attenuator 100, which receives an impacting vehicle. The term "downstream" refers to the position or orientation moving away from the impact end 120 and toward the attachment end 180 of the crash attenuator 100, while the term "upstream" refers to the position or orientation moving toward the impact end 120 and away from the attachment end 180 of the crash attenuator 100. Therefore, for example, a component positioned downstream of another component is closer to the attachment end 180, and vice versa, a component positioned upstream of another component is closer to the impact end 120. The term "outboard" refers to the direction or orientation towards the outermost edges of the crash attenuator 100, while the term "inboard" refers to the direction or orientation away from the outermost edges and towards the center of the crash attenuator 100. The term "upper" refers to the vertical direction or orientation towards the top most edge of the crash attenuator

65

100, while the term "lower" refers to the vertical direction or orientation towards the ground.

Turning now to the drawings, FIGS. 1-6 illustrate a crash attenuator 100 incorporating preferred embodiments of this invention. Referring to FIG. 1, the crash attenuator 100 includes guide collar assemblies 110, an impact end 120, deflecting members 130, a suspension assembly 140, wheels 150, deforming collar assemblies 160, a cross-brace assembly or frame 170, an attachment end 180, and two laterally spaced pairs of deformable attenuator members 190. The lower laterally spaced pair of deformable attenuator members 190 includes proximate ends 194 and distal ends 196, while the upper laterally spaced pair of deformable attenuator members 190 includes proximate ends 192 and distal ends 198. The attenuator members 190 are preferably long steel tubes having a 3 inch diameter circular cross section and 0.125 inch wall thickness. Of course, it should be understood that the attenuator members 190 may be made from other materials, such as aluminum, polymers, composites, or other suitable materials having wall thicknesses greater or less than 0.125 inches, as well as being configured with non-circular cross sectional shapes such as square, rectangular, octagonal, and the like.

Referring to FIG. 2, the crash attenuator 100 further comprises axle anchor plates 242, inboard deforming members 212, and outboard deforming members 214. Preferably, the crash attenuator 100 includes two guide collar assemblies 110. Each guide collar assembly 110 includes two attenuator receivers 111. The attenuator receivers 111 include an inboard deforming member 212, and an outboard deforming member 214. A fastener hole 112 (shown in FIG. 6) is disposed on the inboard surface of each of the attenuator receivers 111.

Referring to FIGS. 3A and 3B, the impact end 120 comprises an impact member 300 that is preferably 73.24 inches in width at its widest point. Of course it should be understood that the impact member 300 may be wider or narrower than 73.24 inches. The impact member 300 includes an impact surface member defining an impact surface 321 having a central portion 322 and side portions 324, a frame structure 325, inner attenuator guide members 326, and upper and lower attenuator guide members 328. The impact member 300 includes deflecting members 130. Each deflecting member includes an input end 332 and an output end 334. Preferably, the impact member 300 has four deflecting members, each deflecting member corresponding to and positioned to engage a deformable attenuator member 190.

Referring to FIG. 4, the attachment end 180 of FIG. 1 comprises a vehicle attachment assembly 400. The vehicle attachment assembly 400 includes a vehicle hitch receiving member 484, deformable attachment member 482, upper attenuator member braces 498, and lower attenuator member braces 496. Each of the upper and lower attenuator member braces includes a through bolt hole 492. The vehicle attachment assembly 400 also includes two cross-brace attachment members 490, and a distal end support frame 410.

Referring to FIGS. 5A-5D, the deforming collar assemblies 160 of FIG. 1 comprise a plurality of deforming members 510, a connecting member 520, a cross-brace attachment member 530, and a pair of receiving [collar] collars 540. The deforming member 510 includes a leading edge 512 and a trailing edge 514.

Referring to FIG. 6, the suspension assembly 140 includes an integrated suspension axle 644, [the] a pair of axle anchor [plate] plates 242, a pair of collar anchor [plate] plates 660, and a pair of collar receiver [channel] channels 670. The

suspension assembly 140 also includes a pair of wheel axles 648, and a pair of lever arms 646.

Referring to FIGS. 3A and B, the impact surface 321 is [rigidly attached to] disposed on the rearward most face of the impact member 300, and is wide enough to protect the maintenance vehicle 3 or the like towing the crash attenuator 100. The central portion 322 of the impact surface 321 lies substantially in a laterally extending vertical plane tangent to the rearward most surface of the frame structure 325. The central portion 322 is preferably 24 inches wide and is preferably positioned such that the horizontal center of the central portion 322 coincides with the horizontal center of the impact surface 321. Two side portions 324 of the impact surface 321 extend laterally outward from the outermost edges of the central portion 322, and extend longitudinally toward the attachment end 180 from the central portion 322 such that they form an acute angle, preferably 30 degrees, with the vertical plane when viewed from above. Of course it should be understood that the central portion 322 may be wider or narrower than 24 inches, and the side portions 324 may be positioned such that they form an acute angle with the vertical plane that is greater or less than 30 degrees.

The impact surface [321] member is attached to the frame structure 325. The frame structure itself is comprised of a plurality of tubular members, preferably having a square cross section, that are preferably rigidly fixed to each other by welding. Of course it should be understood that the frame members may be solid or tubular members of any cross section, and can be fixed by chemical bonding, or mechanical connections such as bolts, screws or rivets as is known in the art.

In operation, the frame structure 325 acts as a lightweight, rigid support that resists deformation during impact, and provides reaction surfaces for the deflecting members 130 and the impact surface 321.

The deflecting members 130 are preferably a continuously curved $\frac{1}{4}$ inch thick metal plate having a 16 inch radius, although other curvatures would also be suitable, including various continuously curved, but non-circular surfaces. Of course it should be understood that the deflecting members may be metal plates having thicknesses greater or less than $\frac{1}{4}$ inch, and may also be made of materials other than metal, such as high density polymers, ceramics, or composites. Each of the deflecting members 130 are attached to the frame structure 325 at the input end 332 and the output end 334, but are preferably attached at multiple points along the rear surface to the frame structure 325 to provide a more supportive reaction surface for the deflecting members 130 during impact. The input end 332 of the deflecting members 130 are attached to the frame near the outboard edge of the frame structure 325, while the output end 334 of the deflecting members 130 is attached to the frame near the portion of the frame structure 325 supporting the central portion 322 of the impact surface 321. The output end preferably wraps around greater than 90 degrees, such that the output end is directed at least partially in a downstream direction.

The upper and lower attenuator guide members 328 are rigidly attached to the upper and lower edges of the deflecting members 130 as well as the frame structure 325. The inner attenuator guide members 326 are rigidly fixed to the innermost edge of the upper and lower attenuator guide members 328, such that the inner attenuator guide members 326 and the upper and lower attenuator guide members 328 form a guide channel that guides each of the deformable attenuator members 190 toward and along the curved surface of the deflecting members 130 when the impact surface is impacted by a vehicle.

Referring to FIG. 2, the guide collar assemblies 110 are rigidly connected to the impact end 120, preferably by a mechanical connection such as bolts, screws or rivets, or by welding or combinations thereof. Specifically, the guide collar assemblies 110 are rigidly attached to the upper and lower attenuator guide members 328. Of course, it should be understood that the guide collar assemblies 110 may also be rigidly attached by welding, bonding, or the like.

Each guide collar assembly includes at least one inboard deforming member 212 and one outboard deforming member 214, both of which are rigidly attached to each of the attenuator receivers 111. Both the inboard and outboard deforming members 212 and 214 are preferably inserted through slots cut into the attenuator receivers 111, and are thereafter fixedly secured thereto. The slots receiving the inboard deforming members 212 are disposed on the inboard side of the attenuator receivers 111 toward the rearward end of the attenuator receivers 111, and adjacent to the corresponding deflecting member 130. However, the inboard deforming [member] members 212 preferably [does] do not extend beyond the rearward most end of the attenuator [receiver] receivers 111. The slots receiving the outboard deforming members 214 are disposed downstream of the inboard deforming members 212 on the outboard side of the attenuator receivers 111.

Both the inboard and outboard deforming members 212 and 214 are configured to be inserted through the slots such that the deforming members 212 and 214 at least minimally engage the deformable attenuator member 190 during impact. However, the degree of engagement between the inboard and outboard deforming members 212 and 214 may be tuned by increasing or decreasing the depth of insertion, or the amount of protrusion into the interior space of the deformable attenuator member. Of course, it should be understood that the inboard and outboard deforming [member] members 212 and 214 may also be rigidly attached to the inside wall of the attenuator receivers 111, instead of inserted through a slot.

As shown in FIG. 6, the upper end of [a] each collar receiving channel 670 is attached to the bottom of [the] a respective guide collar assembly 110, while the bottom end of [the] each collar receiving channel 670 is attached to [the] a respective collar anchor plate 660. Each collar anchor plate 660 is rigidly secured to [the] a respective axle anchor plate 242 using mechanical fasteners such as bolts, rivets, or the like, or by welding or combinations thereof. [The] Each axle anchor plate 242 is attached to the suspension assembly 140. More specifically, [the] each axle anchor plate 242 is attached to the integrated suspension axle 644, preferably by welding, or with mechanical fasteners or combinations thereof. In one embodiment, the suspension axle 644 is a torsion/suspension axle assembly, such as a TorFlex® axle, which includes a rectangular main axle, and a pair of wheel axles 648 secured thereto with a pair of lever arms 646 that rotate against a biasing force created by a torsion spring. The wheels 150 are attached to the wheel axles 648. Of course, it should be understood that other axle configurations may be utilized, such as a rigid/straight axle, or other suspension axles, including for example, and without limitation, leaf or compression springs with dampening systems.

The wheels of the suspension assembly 140 are positioned near the impact end 120 to support the weight of impact member 300, and prevent excessive gyration/vibration/displacement while the crash attenuator 100 is being towed by a maintenance vehicle 3 or the like.

As shown in FIGS. 1 and 2, the crash attenuator 100 preferably includes two pairs of deformable attenuator mem-

bers 190 having equal lengths. In order to maximize lateral stability during impact, each pair of the deformable attenuator members 190 are spaced apart laterally such that the deformable attenuator members 190 are disposed at the 5 outboard edges of the impact member 300. The two pairs of laterally spaced deformable attenuator members 190 are also vertically spaced apart to increase stability. In a preferred embodiment, the two pairs of deformable attenuator members 190 are vertically spaced such that the vertical center of 10 the combined deformable attenuator bending resistance is placed approximately midway between the center of gravities of a small car fulfilling the 820C requirements of the NCHRP 350 test criteria, and a large vehicle fulfilling the 2000P requirements of the NCHRP 350 test criteria. Of 15 course, it should be understood that the deformable attenuator members 190 may be spaced laterally or vertically at any distance within the crash attenuator 100.

Referring to [FIG.] FIGS. 2 and 6, a threaded attachment member (not shown), such as a [riv nut] Rivnut® (blind-installed, internally-threaded rivet) or weldnut, is attached near the proximate ends 192 and 194 of the deformable attenuator members 190. The threaded attachment member is preferably attached at the same distance from the proximate ends 192 for the upper laterally spaced pair of deformable attenuator members 190 and the proximate ends 194 for the lower laterally spaced pair of deformable attenuator members 190. The proximate ends 192 and 194 of the deformable attenuator members 190 are partially inserted into the downstream end of the attenuator receivers 111. 20 Each of the deformable attenuator members 190 are attached to the guide collar assemblies by a single threaded fastener, that is of sufficiently low strength to shear off upon impact with a vehicle. [The] Each threaded fastener is inserted through [the] a respective fastener hole 112 and threads into [the] a respective threaded attachment member thereby 25 securing [the] respective deformable attenuator members 190 to the guide collar assemblies 110. The threaded fasteners preferably have a diameter of $\frac{3}{8}$ inches and are made of SAE J429 Grade 5 steel, but are not limited thereto. When 30 attached to the respective guide collar assemblies 110, the proximate ends 192 and 194 do not contact the deflection members 130, and preferably do not extend past the rearward most ends of the attenuator receivers 111 prior to impact, but rather are spaced downstream from the impact 35 surfaces of the deflection members.

In one embodiment, the proximate ends 192 of the upper pair of laterally spaced deformable attenuator members 190 and the proximate ends 194 of the lower pair of laterally spaced deformable attenuator members 190 are spaced downstream from the input end 332 of the deflecting members 130 at different distances, such that the proximate ends 192 are spaced downstream of the proximate ends 194. In this embodiment, the fastener holes 112 of the attenuator receivers 111 are spaced such that the fastener hole 112 corresponding to the threaded attachment member attached near the proximate end 192 is disposed downstream of the fastener hole 112 corresponding to the threaded attachment member attached near the proximate end 194.

In an alternative embodiment, the proximate ends 194 60 may be spaced downstream of the proximate ends 192 with the corresponding fastener holes 112 spaced accordingly. In yet another alternative embodiment, as viewed from the impact end 120 in the direction of traffic flow 2, the left proximate end 192 may be spaced downstream of the right proximate end 192 of the upper pair of deformable attenuator members 190 and vice versa the right proximate end 192 may be spaced downstream of the left proximate end 65 192.

192. Additionally, the right proximate end 194 may be spaced downstream of the left proximate end 194 of the lower pair of deformable attenuator members 190, and vice versa, the left proximate end 194 may be spaced downstream of the right proximate end 194. Of course it should be understood that any combination of offset spacing of the proximate ends 192 and 194 of the upper and lower deformable attenuator members 190 described above is possible.

This staggered fastener hole spacing simplifies manufacturing and reduces costs because four identically sized deformable attenuator members 190 having identical placement of the threaded attachment members relative to the proximate ends 192 and 194 can be used to achieve the staggered spacing configuration between the upper and lower pairs of deformable attenuator members 190. Of course, it should be understood that the staggered configuration of deformable attenuator members 190 can be achieved by spacing the proximate ends 194 downstream of the proximate ends 192, spacing one of the proximate ends 192 downstream of the other proximate end 192, or using deformable attenuator members 190 of different lengths.

Referring to [FIG.] FIGS. 1 and 4, the [distal ends 198 and 196 of the] upper and lower pairs of deformable attenuator members 190 extend longitudinally from the attenuator receivers 111 of the guide collar assembly 110 to the attachment end 180, and include vertical anchor holes (not shown). Specifically, the distal ends 198 and 196 terminate at and are rigidly attached to the attenuator member braces 496 and 498. The attenuator member braces 496 and 498, shown in FIG. 4, are disposed around the distal ends 198 and 196, and include through bolt holes 492. Preferably, the deformable attenuator members 190 are attached to the attenuator braces 496 and 498 by inserting a $\frac{1}{2}$ inch or similar bolt or connecting pin through the bolt holes 492 and the vertical anchor holes in the deformable attenuator members 190.

The distal end support frame 410, which spans the lateral and vertical distances between the attenuator braces 496 and 498, is attached to the attenuator braces 496 and 498. The rearward end of the two deformable attachment members 482 are rigidly attached near the outboard edges of the forward face of the distal end support frame 410, and extend inwardly downstream where they are attached to the vehicle hitch receiving member 484. The vehicle hitch receiving member 484 is configured to releasably secure the crash attenuator 100 to a maintenance vehicle 3 or the like. Preferably, the vehicle hitch receiving member is configured to be releasably rotatably secured to a maintenance vehicle's 3 towing hitch, and may include for example a component (not shown) adapted to engage a pintle hook or like coupling device.

Two cross-brace attachment members 490 are rigidly attached to the outboard edges of the rearward face of the distal end support frame 410, and extend inwardly upstream. The forward most end of a *respective* cross brace member 174 is attached to each of the cross-brace attachment members 490, while the rearward most [end] ends of the cross brace [member] members 174 [is] are attached to the attachment [member] members 530 of the deforming collar [assembly] assemblies 160. The cross brace members 174 are preferably attached to [the] a *respective* attachment member 530 with a bolt, or other mechanical fastener, or by welding or combinations thereof.

Referring to [FIG. 5] FIGS. 1, 5A and 5B, each deforming collar assembly 160 is disposed around a pair of vertically spaced deformable attenuator members 190. The deforming collar assembly 160 includes two receiving collars 540.

Each receiving collar 540 is disposed around the outer surface of one of the pair of vertically spaced deformable attenuator members 190. The upper and lower receiving collars [520] 540 are connected by and fixedly attached to the connecting member 520. Each deforming collar assembly 160 also includes a plurality of deforming members 510 configured to engage the deformable attenuator members 190.

The deforming collar assemblies 160, or the alternative 10 deforming collar assemblies 160', preferably include four deforming members 510, 510' disposed along axes neutral to the bending moment resulting from the deformation of the deformable attenuator members 190 during impact. [Each] Referring to FIGS. 5C and 5D, each deforming member 510, 510' has a leading edge 512, 512' disposed upstream from the trailing edge 514, 514'. The portion of the deforming member 510, 510' that engages the deformable attenuator member 190 is preferably formed in a ramp or semi-circular shape, as shown in FIGS. 5C and 5D. The deforming members 510, 510' are rigidly attached to the receiving collars 540, and are preferably inserted through slots cut into the receiving collars 540. The degree of engagement between the inboard and outboard deforming members 510, 510' may be tuned by increasing or decreasing the depth of insertion of the deforming members 510, 510' into the receiving collars 540. The two deforming collar assemblies 20 are connected by a lateral brace bar 172, which helps prevent the deformable attenuator members 190 from buckling in the horizontal plane during impact. In one embodiment, only an upper and lower deforming member are attached to the receiving [collar] collars, with the deforming members being vertically aligned along a neutral bending axis of the respective deformable member such that the deformation of the deformable members by the deforming members does not significantly modify the bending characteristics (moment of inertia) of the deformable member.

In operation, the crash attenuator 100 is attached to a receiver hitch located at the front or rear of a maintenance vehicle 3 or the like by the vehicle hitch receiving member 484. This configuration allows the crash attenuator 100 to be towed and rotated similar to a standard trailer assembly. The attenuator braces 496 and 498 operate to restrain the distal ends of the deformable attenuator members 190 in impact. The crash attenuator 100 is configured to attenuate crash energy from vehicles traveling in the direction of traffic flow 2 that impact the impact member 300 in an axial or offset direction.

In the event of an axial impact, the impacting vehicle primarily contacts the central portion 322 of the impact surface 321. In an offset impact the vehicle primarily loads only one side of the central portion 322 of the impact surface 321, but does not significantly load the corresponding side portion 324. Because the side portion 324 is angled toward the attachment end 180, offset impacts load the impact member 300 more evenly, which reduces the eccentric effect on the crash attenuator 100 and therefore results in a reduced bending moment applied to the deformable attenuator members 190.

When a vehicle impacts the impact member 300, the impact forces the impact surface 321 against the frame structure 325 and accelerates the entire impact end 120 and all the components rigidly attached thereto, including the impact member 300, the guide collar assemblies 110, and the suspension assembly 140 in a longitudinal direction toward the attachment end 180.

The wheels, which are engaged with the ground, help guide the crash cushion or attenuator in the longitudinal

11

direction [2] 1 during impact. Furthermore, because the suspension assembly 140 is rigidly connected to the impact member 300 through the guide collar assemblies 110, the suspension assembly 140 helps prevent the impact member 300 from being deflected downward during impact.

As the impact end 120 moves longitudinally toward the attachment end 180, the threaded fasteners connecting the deformable attenuator members 190 to the guide collar assemblies 110 are sheared off by the attenuator [receiver] receivers 111, thereby decoupling the deformable attenuator members 190 from the attenuator receivers 111. Of course it should be understood that the threaded fasteners may be decoupled by means other than shearing, such as ejecting the threaded fastener. The impact end 120 then moves along the deformable attenuator members 190, which are connected to the maintenance vehicle 3 by the attachment end 180, and thus remain stationary.

Once the attenuator receivers 111 have become decoupled from the deformable attenuator members 190, the attenuator receivers 111 move along the deformable attenuator [member] members 190 as the impact member 300 is forced towards the attachment end 180 by the impacting vehicle. As the attenuator receivers 111 move along the deformable attenuator members 190, the inboard and outboard deforming members 212 and 214 engage the deformable attenuator [member] members 190, which has a stabilizing effect on the deformable attenuator members 190. In the event the impact member 300 rotates due to the impact force, for example in the event of an offset impact, the inboard and outboard deforming members 212 and 214 are configured to engage the deformable attenuator member 190 on the side of the offset impact. This engagement introduces a corresponding deforming force in the deformable attenuator member 190 closest in proximity to the rotational moment source, without increasing force in the other deformable attenuator members 190. As such, the impact member tends to move uniformly along both sets of deformable attenuator members. During this initial stage of impact, the deformable attenuator members 190 are spaced away from the deflecting member 130 and the decelerating force exerted on the vehicle by the crash attenuator [300] 100 is substantially limited to the acceleration of the mass of the impact end 120, including the suspension assembly 140 and impact member 300. Thus, the vehicle and its occupants are subjected to an acceptable delta V, as specified in the NCHRP 350 specification.

As the attenuator receivers 111 continue to move longitudinally downstream, the proximate ends 194 of the deformable attenuator members 190, which are spaced closest to the deflecting members 130 move along the upper and lower attenuator guide members [326] 328 and contact the input [end] ends 332 of the continuously curved [surface] surfaces of the deflecting [member] members 130. As the proximate ends 194 of the deformable attenuator members 190 move along the [surface] surfaces of the deflecting [member] members 130, the lower pair of deformable attenuator members 190 is bent inwardly, thereby absorbing energy. Preferably, the bending forces cause the deformable attenuator members 190 to kink at set intervals, which produces a continuous curling affect as the attenuator receivers 111 move longitudinally downstream towards the attachment end 180. Each time a deformable attenuator member 190 kinks, it results in a spike in energy absorption, which results in a spike in ride-down g for the impacting vehicle and its occupants. In one embodiment, the deformable attenuator members kink at 12 inch intervals, with the ends of the

12

deformable members being longitudinally staggered or offset from each other at a distance of 6 inches.

Shortly after the proximate ends 194 of the lower pair of deformable attenuator members 190 contact the deflecting [member] members 130, the proximate ends 192 of the upper pair of deformable attenuator members 190 contact the deflecting [member] members 130, such that the proximate ends 194, 192 of the lower and upper pairs are successively deformed. The upper pair of deformable attenuator members 190 is bent inwardly in the same manner described above with regard to the lower pair of deformable attenuator members 190. Because the deformable attenuators 190 kink at set intervals, by staggering the spacing of the proximate ends 192 and 194 from the deflecting [member] members 130 only two deformable attenuator members 190 will kink at any given time. Therefore, in this staggered configuration the vehicle and its occupants will only experience a decelerating force equal to the energy absorbed by kinking one pair of deformable attenuator members 190 at any given time. Of course it should be understood that the positioning of the proximate ends 192 and 194 is not limited to the staggered configuration described above and any configuration of the left and right proximate ends 192 and 194 of the upper and lower pairs of deformable attenuator members 190 such that two of the proximate ends 192 or 194 are spaced downstream from the remaining two proximate ends 192 or 194 may be used.

In operation, the cross-brace assembly or frame 170 is configured to increase the lateral rigidity of the crash attenuator 100 and prevent inboard or outboard buckling due to the bending moment exerted on the deformable attenuator members 190 during bending. The cross-brace assembly 170 also reduces the effective length of the deformable attenuator members 190 thereby reducing the tendency to buckle due to a compression load as the deformable attenuator members 190 are deformed during impact.

In the case of a small vehicle impact, the impacting vehicle is decelerated within the NCHRP 350 specification limits prior to the impact end 120 contacting the cross-brace assembly 170. Thus, the cross-brace assembly 170 is not configured to deform under a small vehicle impact. However, the cross-brace assembly 170 is configured to deform under an axial or offset impact by a large vehicle.

When a large vehicle fulfilling the 2000P requirements of the NCHRP 350 test criteria impacts the crash attenuator 100, the initial stages of crash attenuation and energy absorption are identical to those described above. However, during a large vehicle impact, the forward most end of the attenuator receivers 111 contact the rearward most face of the receiving [collar] collars 540 and with enough force to accelerate the cross-brace assembly 170 toward the attachment end 180. This in turn causes the leading [edge] edges 512 of the deforming members 510 to engage the deformable attenuator members 190. As the attenuator receivers 111 continue to move longitudinally downstream, the deformable attenuator members 190 are increasingly deformed as the outer [surface] surfaces of the deformable attenuator members 190 [travels] travel along the [surface] surfaces of the deforming members 510 from the shallow leading [edge] edges 512 to the deeper trailing [edge] edges 514. This deformation reduces a cross-sectional area of the deformable attenuator members 190 as shown in FIG. 5B. Because the deforming collar assemblies 160 are rigidly connected to the cross-brace members 174, the cross-brace members 174 are also configured to deform as the deforming collar assemblies 160 are forced downstream toward the attachment end 180.

The deformable attachment members 482 of the attachment end 180 are configured to remain rigid during both small and large vehicle axial impacts. However, during an offset large vehicle impact, the deformable attachment members 482 are configured to deform, preferably in an upward direction. This deformation of the deformable attachment members 482 causes the vehicle attachment assembly 400 to hinge about the hitch mount of the maintenance vehicle 3, and allows the crash attenuator 100 to pivot away from the vehicle and direct the impacting vehicle away from the maintenance vehicle 3.

FIG. 7 illustrates an alternative embodiment of the crash attenuator 100 that further comprises secondary deformable attenuator members disposed within the deformable attenuator members 190. The secondary deformable attenuator members 790 are deformable members having an outer diameter that is small enough to fit inside the deformable attenuator members 190. Preferably, the secondary deformable attenuator members 790 are metal tubes having a circular cross section and an outer diameter that is a predetermined amount less than the inner diameter of the deformable attenuator members 190. Of course, it should be understood that the secondary deformable attenuator members 790 may be solid or hollow structures, and may be made of metal, polymers, composites, or other suitable energy absorbing materials.

The secondary deformable attenuator members have proximate ends 792 and 794 and distal ends 796 and 798. The proximate ends 792 and 794 of the secondary deformable attenuator members 790 are inserted at the distal ends 196 and 198 of the deformable attenuator members 190, and may be evenly spaced, or staggered to mirror the ridedown spikes in a manner that is consistent with the deformable attenuator members 190. The secondary deformable attenuator members 790 are preferably shorter in length than the deformable attenuator members 190. The distal ends 796 and 798 of the secondary deformable attenuator members 790 are coupled to the distal ends 196 and 198 of the deformable attenuator members [196 and 198] 190. Thus in this alternative embodiment of the crash attenuator 100, the deformable attenuator members 190 include a secondary deformable attenuator member 790 disposed within and extending partially down the longitudinal length of the deformable attenuator members 190.

Preferably, each of the secondary attenuator members 790 are the same length, and thus extend down the deformable attenuator members 190 an equal distance. The portion of the deformable attenuator members 190 extending past the proximate ends 792 and 794 of the secondary deformable attenuator members 790, defines a first energy absorption zone (Z1), while the portion of the deformable attenuator members 190 extending from the distal ends 798 and 796 to the proximate ends 792 and 794 of the secondary deformable attenuator members 790 defines a second energy absorption zone (Z2), which absorbs more energy than the first energy zone (Z1).

In operation, the alternative embodiment absorbs energy through the same bending and deforming mechanisms described above with regard to the crash attenuator 100 of FIG. 1. However, when the proximate ends 792 and 794 contact the input [end] ends 332 of the continuously curved [surface] surfaces of the deflector [member] members 130, the total energy absorption of the crash attenuator 100 is increased by the additional energy required to bend the secondary deformable attenuator members 790 disposed within the deformable attenuator members 190. In this way, the operation includes deforming a first portion of deform-

able attenuator member 190 without deforming the secondary deformable member 790 and deforming a second portion of the deformable attenuator member 190 housing the secondary deformable member 790 while simultaneously deforming the secondary deformable member 790. Additional energy is absorbed in like fashion when the attenuator receivers 111 contact the deforming collar assemblies 160 and cause the leading [edge] edges 512 of the deforming members 510 to engage the deformable attenuator [member] members 190 to the extent deforming members 510 also deform the secondary deformable attenuator members 790.

FIGS. 8A-9C illustrate alternative embodiments of the deflecting [member] members 130. FIG. 8A illustrates a top view of [a] bending [pipe] pipes 830, [and] or curved tubular deflecting members. FIG. 8B illustrates a perspective view of the bending [pipe] pipes 830, or curved tubular deflecting members. In FIGS. 8A-8B, [the] each tubular deflecting member is a bending pipe 830 positioned upstream of the deforming members 212, 214 and having a continuously curved radius and an inner diameter larger than the outer diameter of the deformable attenuator members 190. [The] Each bending pipe 830 has an inlet end 832 and an outlet end 834 that bends inward toward the center of the crash attenuator.

When [the] each deformable attenuator member 190 is forced through [the] a respective bending pipe 830, after the deformable attenuator member 190 is engaged with a respective pair of deforming members 212, 214, the outer surface of the deformable attenuator member contacts the inlet end 832 marking the beginning of the inward bend. As the deformable attenuator member 190 is forced through the respective bending pipe 830, the deformable attenuator [members] member 190 [deform] deforms along the inside surface of the bending pipe and [exit] exits at the outlet end 834 of the bending pipe 830. Because the deformable attenuator member 190 is forced to follow the continuously curved radius of the respective bending pipe 830, the deformable attenuator member emerges from the bending pipe 830 having a radius substantially equivalent to the radius of the bending pipe 830. The outlet end can extend greater than 90 degrees such that [it] the outlet end is at least partially directed downstream and the proximate ends 192, 194 are pointed in at least a partially downstream direction after the impact member is moved to the impact position.

FIG. 9A illustrates a top view of [a] deforming deflecting [member] members 930 prior to impact. FIG. 9B illustrates a top view of the deforming deflecting [member] members 930 after impact. FIG. 9C illustrates a perspective view of one of the deforming deflecting [member] members 930 prior to impact. [The] Each deforming deflecting member 930 includes an input end and an output end that are connected by a straight linear face creating an obtuse angle with the longitudinal axis of the respective deformable attenuator member 190. The straight deflecting face 910 of [the] each deforming deflecting member 930 has a height that is less than the diameter of the respective deformable attenuator member 190 and is positioned such that the vertical center of the deflecting face 910 is in line with the central axis of the deformable attenuator member 190.

When the deformable attenuator member 190 is forced against the input edge 932 of the deforming deflecting member 930, the outer surface of the deformable attenuator member 190 contacts the straight deflecting face 910 and causes the deformable attenuator member 190 to deform inwardly and thereby absorb energy.

FIGS. 10A and 10B illustrate another alternative embodiment of the crash attenuator 100. The crash attenuator 1000

includes essentially the same elements as the crash attenuator 100 but arranged in a flip-flopped configuration with the proximate ends 192 and 194 of the deformable attenuator members 190 rigidly attached to the impact end 120, and the deflecting members 130 rigidly attached to the attachment end 180.

In the crash attenuator 1000, when a vehicle impacts the impact end 120, it accelerates the mass of the impact end 120, and all the components rigidly attached thereto, including the deformable attenuators 190, the cross brace assembly 170, and the suspension assembly 140. The distal ends 196 and 198 of the deformable attenuator members 190 are spaced longitudinally upstream from the deflecting members 130 in the pre-impact position. Preferably, the distal ends of the upper and lower laterally spaced deformable attenuator members 190 are staggered upstream from the deflecting members 130, as described above with regard to FIGS. 1-6. The guide collar assemblies 110, including the attenuator receivers 111 and inboard and outboard deforming members 212 and 214, are rigidly attached to an attachment end frame assembly 1025. A lateral brace 1010 extends laterally between and connects the two guide collar assemblies 110 and helps prevent inboard and outboard buckling during impact.

As the impact end 120 moves downstream toward the attachment end 180, the distal ends 196 and 198 of the deformable attenuator members 190 engage the inboard and outboard deforming members 212 and 214 of the guide collar assemblies 110, which are attached to [an] the attachment end frame assembly 1025. The distal ends 196 and 198 then contact the input end 332 of the deflecting members 130 and travel along the continuously curved surface to the output end 334, which causes the deformable attenuator members 190 to bend inward.

During a large vehicle impact, the impact end 120 forces the forward end of the deforming collar assemblies 160 against the rearward end of the attenuator receivers 111, which causes the deforming members 510 to engage the deformable attenuator members 190.

Alternatively, the crash attenuator 1000 may also incorporate secondary deformable attenuator members 790 disposed within the deformable attenuator members 190 as described above with regard to FIG. 7. In this configuration, the proximate ends 792 and 794 are coupled to the proximate ends 192 and 194, and the secondary attenuator members 790 extend partially down the length of the deformable attenuator members 190 in a longitudinally downstream direction toward the attachment end 180. As the impact end 120 moves toward the attachment end 180 the secondary deformable attenuator members are deformed as described above with regard to FIG. 7

FIG. 11 illustrates a fixed anchor embodiment of a crash attenuator. The crash attenuator 1100 includes an impact member 1120, deflecting members 1130, attenuator receivers 1110, a cross brace assembly 1170, deforming collar assemblies 1160, and deformable attenuator members 1190 having distal ends 1196 and proximate ends 1192 that are spaced longitudinally downstream of the deflecting members 1130. The impact member includes a central portion 1122 and two side portions 1124 adjacent to the central portion 1122 and extending longitudinally toward the distal [end] ends 1196 of the deformable attenuator members 1190, such that the side portions 1124 are not parallel with the central portion 1122. The deforming collar assemblies 1160 include deforming members 1140. Each attenuator receiver 1110 includes an inboard deforming member 1112 and an outboard deforming member 1114.

The impact member 1120 is rigidly attached to the deflecting [member] members 1130 and the attenuator receivers 1110. The distal ends 1196 of the deformable attenuator members 1190 are rigidly attached to an anchor surface 1180, such as a wall, or other immovable object secured to the ground, or the rear end of a stationary support vehicle. The proximate ends 1192 of the deformable attenuator members 1190 are attached to the attenuator receivers 1110 with [a] shearable [fastener] fasteners 1150. The front ends of the cross brace assembly 1170 are attached to the anchor surface 1180 near the distal end 1196 of the deformable attenuator members 1190, while the rear ends of the cross brace assembly 1170 are attached to deforming collar assemblies 1160 disposed around the deformable attenuator members 1190. The deforming members 1140 are attached to the deforming collar assemblies 1160, and are configured to engage the deformable attenuator [member] members 1190 during impact.

When a vehicle contacts the impact member 1120, the impact member 1120 is accelerated toward the anchor surface 1180. This movement forces the shearable [fastener] fasteners 1150 to shear off, and allows the inboard and outboard deforming members 1112 and 1114 to engage the deformable attenuator members 1190. As the impact member 1120 travels toward the anchor surface 1180, the proximate ends 1192 of the deformable attenuator members 1190 contact the deflecting [member] members 1130. The deformable attenuator members 1190 are then bent inward as the proximate ends 1192 are forced along the continuously curved surface of the deflecting members 1130.

As the forward [surface] surfaces of the attenuator [receiver] receivers 1110 [contacts] contact the rearward [surface] surfaces of the deforming collar assemblies 1160, the deforming collar assemblies are forced downstream toward the anchor surface 1180, which causes the deforming members 1140 to engage the deformable attenuator members 1190.

Although the present invention has been described with reference to preferred embodiments, those skilled in the art will recognize that changes may be made in form and detail without departing from the spirit and scope of the invention. As such, it is intended that the foregoing detailed description be regarded as illustrative rather than limiting and that it is the appended claims, including all equivalents thereof, which are intended to define the scope of the invention.

What is claimed is:

1. A crash attenuator comprising:
a first end adapted to be releasably secured to a vehicle;
a second end longitudinally spaced from said first end and including an impact member moveable in [said] a longitudinal direction from a pre-impact position to an impact position;
spaced apart first and second pairs of deformable attenuator members extending in [a] said longitudinal direction, each of said deformable attenuator members having a proximal end and a distal end, wherein said proximal ends of said second pair of said deformable attenuator members are staggered downstream from said proximal ends of said first pair of said deformable attenuator members when said impact member is in said pre-impact position, and wherein said proximal ends of said first and second pairs of said deformable attenuator members are successively deformed by said impact member as said impact member is moved to said impact position; and

a deforming member engaged with at least a portion of at least one of said deformable attenuator members downstream of said impact member.

2. The crash attenuator of claim 1, wherein said first pair of said deformable attenuator members is vertically spaced from said second pair of said deformable attenuator members. 5

3. The crash attenuator of claim 1, wherein at least some of said deformable attenuator members have a circular cross section. 10

4. The crash attenuator of claim 1, wherein said first pair of deformable attenuator members are laterally spaced and wherein said second pair of deformable attenuator members are laterally spaced. 15

5. The crash attenuator of claim 1, wherein said deforming member is secured to a cross-brace frame extending laterally between at least one of said first and second pairs of deformable attenuator members. 20

6. The crash attenuator of claim 1, wherein said deforming member comprises at least one shaping member configured to engage said at least said portion of said at least one deformable attenuator member, wherein said shaping member is positioned along an axis neutral to the bending moment resulting from a bending of said *at least one* 25 deformable attenuating [members] member.

7. The crash attenuator of claim 1 wherein said distal ends of said second pair of said deformable attenuator members are staggered downstream from said distal ends of said first pair of said deformable attenuator members when said impact member is in said pre-impact position. 30

8. A crash attenuator comprising:
a first end adapted to be releasably secured to a vehicle;
a second end longitudinally spaced from said first end and including an impact member moveable in [said] a 35 longitudinal direction from a pre-impact position to an impact position;

spaced apart first and second pairs of deformable attenuator members extending in [a] *said* longitudinal direction, each of said deformable attenuator members having a proximal end and a distal end, wherein said proximal ends of said second pair of said deformable attenuator members are staggered downstream from said proximal ends of said first pair of said deformable attenuator members when said impact member is in 45 said pre-impact position, and wherein said proximal ends of said first and second pairs of said deformable attenuator members are successively deformed by *said impact member* as said impact member is moved to said impact position; and

a secondary deformable attenuator member housed within at least one of said deformable attenuator members and extending in a longitudinal direction, wherein at least a portion of said secondary deformable attenuator member is deformable by *said impact member* when said impact member is moved from said pre-impact position to said impact position. 50

9. The crash attenuator of claim 8, wherein said secondary deformable attenuator member is shorter in length than said deformable attenuator member housing said secondary 60 deformable attenuator member.

10. A crash attenuator comprising:
a first end adapted to be releasably secured to a vehicle;
a second end longitudinally spaced from said first end and including an impact member moveable in [said] a 65 longitudinal direction from a pre-impact position to an impact position;

spaced apart first and second pairs of deformable attenuator members extending in [a] *said* longitudinal direction, each of said deformable attenuator members having a proximal end and a distal end, wherein said proximal ends of said second pair of said deformable attenuator members are staggered downstream from said proximal ends of said first pair of said deformable attenuator members when said impact member is in said pre-impact position, and wherein said proximal ends of said first and second pairs of said deformable attenuator members are successively deformed by *said impact member* as said impact member is moved to said impact position; and

at least a pair of deforming members coupled to each of opposite sides of said impact member, each of said pair of *deforming* members comprising an inboard deforming member positioned adjacent to an inboard side of one of said deformable attenuator members and an outboard deforming member positioned adjacent to an outboard side of said one of said deformable attenuator members, wherein said outboard deforming [member is] members are positioned longitudinally downstream from said inboard deforming [member] members. 15

11. A crash attenuator comprising:
a first end adapted to be [releasable] *releasably* secured to a vehicle;

a second end longitudinally spaced from said first end and including an impact member moveable in [said] a longitudinal direction from a pre-impact position to an impact position;

spaced apart first and second pairs of deformable attenuator members extending in [a] *said* longitudinal direction, each of said deformable attenuator members having a proximal end and a distal end, wherein said proximal ends of said second pair of said deformable attenuator members are staggered downstream from said proximal ends of said first pair of said deformable attenuator members when said impact member is in said pre-impact position, and wherein said proximal ends of said first and second pairs of said deformable attenuator members are successively deformed by *said impact member* as said impact member is moved to said impact position, wherein said distal ends of said second pair of said deformable attenuator members are staggered downstream from said distal ends of said first pair of said deformable attenuator members when said impact member is in said pre-impact position, and wherein said first and second pairs of [attenuator] deformable attenuator members are substantially the same length. 40

12. A crash attenuator comprising:
a first end;

an impact member located at a second end longitudinally spaced from said first end;

an energy absorbing member disposed between said second end and said first end and configured to absorb energy when said impact member is moved toward said first end from a pre-impact position to an impact position; and

at least a pair of deforming members coupled to said impact member, said pair of deforming members comprising an inboard deforming member positioned adjacent to an inboard side of said energy absorbing member and an outboard deforming member positioned adjacent to an outboard side of said energy absorbing member, wherein said deforming members are configured to engage said energy absorbing member as said

impact member is moved from said pre-impact position to said impact position, and wherein said outboard deforming member is positioned longitudinally downstream from said inboard deforming member.

13. A method of decelerating a vehicle with a crash attenuator, said method comprising:

providing a crash attenuator comprising an impact member, spaced apart first and second pairs of deformable attenuator members extending in a longitudinal direction, each of said deformable attenuator members having a proximal end and a distal end, wherein said proximal ends of said second pair of said deformable attenuator members are staggered downstream from said proximal ends of said first pair of said deformable attenuator members;

10 impacting said impact member with a vehicle; deforming said first pair of deformable attenuator members with a deforming member engaging at least a portion of at least one of said deformable attenuator members downstream of said impact member; and deforming said second pair of deformable attenuator members, wherein said deforming said second pair of deformable attenuator members is initiated after onset of said deforming of said first pair of deformable attenuator members.

15 14. A method of decelerating a vehicle with a crash attenuator, said method comprising:

providing a crash attenuator comprising an impact member, spaced apart first and second pairs of deformable attenuator members extending in a longitudinal direction, each of said deformable attenuator members having a proximal end and a distal end, wherein said proximal ends of said second pair of said deformable attenuator members are staggered downstream from said proximal ends of said first pair of said deformable attenuator members;

releasably securing said crash attenuator to a first vehicle;

impacting said impact member with a second vehicle; deforming said first pair of deformable attenuator members; and

deforming said second pair of deformable attenuator members, wherein said deforming said second pair of deformable attenuator members is initiated after onset of said deforming of said first pair of deformable attenuator members, wherein said crash attenuator further comprises a secondary deformable attenuator member housed within at least one of said deformable attenuator members and extending longitudinally therein; and [wherein said deforming said at least one of said deformable attenuator members housing said secondary deformable member comprises] wherein said at least one of said deformable attenuator members housing said secondary deformable attenuator member is deformed by deforming a first portion of said at least one deformable attenuator member without deforming said secondary deformable member and deforming a second portion of said at least one deformable attenuator member housing said secondary deformable member while simultaneously deforming said secondary deformable member.

16 15. A method of decelerating a vehicle with a crash attenuator, said method comprising:

providing a crash attenuator comprising an impact member, at least a pair of laterally spaced deformable attenuator members, [a] and at least a pair of deflecting [member] members, wherein proximal ends of said

deformable attenuator members are spaced downstream from said deflecting [member] members; impacting said impact member with a vehicle and moving said impact member and deflecting [member] members downstream toward said deformable attenuator members without immediately engaging said deformable attenuator members with said deflecting [member] members;

subsequently engaging said deformable attenuator members with said deflecting [member] members and deforming said deformable attenuator members with said deflecting [member] members; and

deforming said pair of deformable attenuator members with a pair of laterally spaced deforming members engaging at least a portion of said deformable attenuator members downstream of said impact member; and wherein said at least said pair of laterally spaced deformable attenuator members comprises a first pair of said laterally spaced deformable attenuator members; and further comprising a second pair of laterally spaced deformable attenuator members, wherein said second pair of deformable attenuator members have proximal ends spaced downstream from said proximal ends of said first pair of deformable attenuator members, and engaging said second pair of deformable attenuator members with said deflecting members after engaging said first pair of said deformable attenuator members with said deflecting members.

16. The method of claim 15 further comprising a second pair of laterally spaced deformable attenuator members, wherein said second pair of deformable attenuator members have proximal ends spaced downstream from said proximal ends of said first pair of deformable attenuator members, and engaging said second pair of deformable attenuator members with said deflecting member after engaging said first pair of said deformable attenuator members with said deflecting member.]

17. A crash attenuator comprising:

a first end; a second end longitudinally spaced from said first end and including an impact member moveable in a longitudinal direction from a pre-impact position to an impact position;

a deformable attenuator member extending in said longitudinal direction, said deformable attenuator member having a proximal end and a distal end; a pair of deforming members engaged with opposite sides of at least a portion of said deformable attenuator member downstream of said impact member; and a curved, tubular deflecting member positioned upstream of said deforming members, said deflecting member shaped to receive and bend said deformable attenuator member after said deformable attenuator member is engaged with said pair of deforming members.

18. The crash attenuator of claim 17, wherein each of said pair of deforming members are shaped to reduce a cross-sectional area of said deformable attenuator member as said impact member is moved from said pre-impact position to said impact position.

19. The crash attenuator of claim 17, wherein said deformable attenuator member is hollow.

20. The crash attenuator of claim 17, wherein said proximal end of said deformable attenuator member is pointed in at least a partially downstream direction after said impact member is moved to said impact position.

21. The crash attenuator of claim 17, wherein said deformable attenuator member comprises a first deformable

21

attenuator member, and further comprising a second deformable attenuator member extending in a longitudinal direction, said second deformable attenuator member having a proximal end and a distal end.

22. The crash attenuator of claim 21, wherein said first 5 and second deformable attenuator members are laterally spaced.

23. The crash attenuator of claim 21, wherein said pair of deforming members comprises a first pair of deforming members engaged with said opposite sides of said first 10 deformable attenuator member, and further comprising a second pair of deforming members engaged with opposite sides of said second deformable attenuator member downstream of said impact member, and wherein said curved, tubular deflecting member comprises a first deflecting member 15 positioned upstream of said first pair of deforming members, and further comprising a second deflecting member positioned upstream of said second pair of deforming members, said second deflecting member shaped to receive and bend said second deformable attenuator member after 20 said second deformable attenuator member is engaged with said second pair of deforming members.
